UNITED STATES PATENT OFFICE.

WALTER N. VANCE, OF CHICAGO HEIGHTS, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS.

RACK.

Application filed June 23, 1928. Serial No. 287,780.

This invention relates to sheet metal racks or shelving and has for its general object to provide an improved construction comprising a minimum number of parts, by which the 5 shelving units of the desired size may be rapidly assembled or disassembled, while also providing for a wide range of and rapid adjustment of the shelving at any desired levels.

10 Numerous other objects and advantages of the invention will be apparent as it is better understood from the following description, which, taken in connection with the accompanying drawings, discloses a preferred embodiment thereof.

Referring to the drawings:

Figure 1 is a vertical sectional elevation taken in a front-to-rear plane of one form of rack unit embodying the invention;

20 Fig. 2 is a horizontal section on the line 2—2 of Fig. 1;

Fig. 3 is a vertical sectional elevation taken from side-to-side or lengthwise of the rack, as indicated by the line 3—3 of Figs. 1 and 2;

25 Fig. 4 is an enlarged fragmentary vertical section of the upper part of the rack taken on the line 4—4 of Fig. 1; and

Fig. 5 is an enlarged fragmentary vertical section of the bottom part of the rack taken 30 on the line 5—5 of Fig. 1.

In its general construction, the illustrative rack or shelf comprises the dividers 11 constituting the sides or ends, the top 12 and bottom 13, the back 14, and the shelves 15, all 35 made of sheet metal to provide the structures hereinafter set forth.

The sides of the rack, or dividers 11 are each made from flat vertical plates and extend in vertical planes from front-to-rear of the rack unit. Each divider is provided 40 along its front vertical edge with flanging 16 bent to form a bulb fold and then rebent to lie substantially flat against the outside face or surface 17 of the divider. Along its rear vertical edge, each divider 11 is formed with vertical flanging 18 bent from the main plane 45 of the divider and projecting inwardly therefrom in the side-to-side or lengthwise dimension of the rack. The rear flanging 18 provides shoulders which cooperate mutually to support the back 14 of the rack as herein- 50 after described.

At their tops and bottoms, the divider plates 11 are also preferably provided with 55 sidewise extending flanging 19 and 20 (Figs.

3, 4 and 5) which project horizontally inwardly from the inside faces 21 of the dividers.

For the purpose of supporting the shelving at different levels, the dividers 11 are 60 provided each with superposed horizontal rows of horizontally-extending elongated louvres 22 punched and bent from the main planes of the dividers and respectively projecting inwardly and upwardly, from their 65 bottom lines 23 of attachment to the opposite inside faces or surfaces 21 of the divider plates. In the illustrative embodiment, the several rows of louvres or supporting projections 22 are arranged in vertical as well as 70 in horizontal alignment, thereby promoting the symmetrical appearance of the divider plates 11. The rows of louvres are spaced vertically the minimum distance permitted 75 between any two adjacent shelves and sufficient louvres are provided preferably to permit of wide variation in the levels of adjustment of the shelving. The extreme bottom row 24 of louvres are punched and bent 80 inwardly from the main planes of the dividers 11 similarly to the other rows 22, but project downwardly from their top lines 25 of attachment to the divider plates, in order to provide for holding down the bottom 13 of the rack.

85 The illustrative rack provides a structure whereby the top 12, bottom 13, back 14, and shelves 15 may be made all substantially uniform in structure and dimensions. Each of these parts may be made from a sheet metal 90 plate 26 cut to the required dimensions and so formed as to function in the rack either as a top, bottom, back or shelf. The plates 26 are provided with flanges 27 extending along their opposite sides and bent so as to project 95 in the same direction substantially perpendicularly to the main planes of the plates. At one end, each plate 26 is formed with flanging 28 bent into a bulb fold and then rebent to lie substantially flat against the 100 same surface of the plate from which the side flanging 27 projects. At its other end, each plate 26 is formed with end flanging 29 bent substantially perpendicularly to the plane of the plate and projecting therefrom in the 105 same direction as the side flanging 27. The opposite ends of the side flanging 27 are bevelled, as shown at 30, from the line of bend convergently towards the free edge of the flanging; and the opposite ends of the 110

end flanging 29 of the plate are bevelled similarly, as shown at 31. In order to provide clearance for the various parts in assembling into rack units, the corners of the plates 26 between the side and end flanging thereof may be bevelled off, as shown at 32.

In constructing a rack unit with the dividers 11 and plates 26 above described, it is only necessary to provide a pair of divider plates 11 for the sides, a pair of plates 26 for the top 12 and bottom 13, a third plate 26 if it be desired to provide a back 14, and such other plates 26 as may be required for the shelves 15. The top 12, bottom 13 and dividers 11 constituting the side walls of a unit may be connected in any convenient sequence by sliding the top and bottom in interengagement with the spaced dividers so that the side flanging 27 of the top plate 12 projects downwardly into the spaces between upper rows of louvres 22 at the same level, and the inside faces 21 of the dividers and the side flanging 27 of the inverted bottom plate 13 project upwardly inside the bottom rows 24 of reversely projecting louvres. If the top 12 and bottom 13 be applied to the extreme top and bottom rows of louvres of the side dividers, the upper face or surface of the top 12 underlies and is embraced by the top side flanges 19 of the dividers and the lower face or surface of the bottom 13 rests upon the bottom side flanging 20.

Whenever a back 14 is employed for the rack unit, one of the plates 26 is positioned with the bulb flanging end 28 lowermost and is turned so that the side flanging 27 will project forwardly of the unit and inside the inner faces 21 of the divider plates. The back 14 may be slid into place by lowering it until the bulb flanging 28 is positioned forwardly of and within the upstanding end flanging 29 of the bottom 13, and the end flanging 29 of the back rests upon the upper surface of the top 12 and the forward inside face of the back engages the end flanging 29 of the top.

Any desired number of shelves 15, within the capacity of the rack unit, may be applied at the levels permitted by the rows of louvres between the top and bottom of the rack unit. The shelves may be rapidly applied or removed by sliding the interengaged side flanging 27 within and relatively to any two rows of louvres 22 located at the same level at opposite sides of the rack unit. When in position, the shelves 15 are pushed back preferably far enough so that their end flanges 29 engage and help support the back 14.

The illustrative rack unit construction hereinbefore described provides a true knock-down structure in which the parts may be rapidly assembled or adjusted to various shelving requirements, without the employment of any extraneous fastening devices whatsoever. Moreover only three structural-

ly different types of parts are required to provide a unit of any predetermined dimensions having a wide capacity for various adjustments of shelving. These parts are the two dividers which differ from each other only 70 in that the louvres 22 and 24 are pressed reversely from the plane of the dividers to provide the right and left sides for the rack unit, and the flanged plates 26 all of which are alike and may be employed for either 75 top, bottom, back, or shelving. Although extremely cheap to manufacture because of the small number of parts, all of which are made of sheet metal by relatively simple factory methods, the units when assembled are strong 80 and durable and the parts remain permanently in adjusted position. The bulb flanging 16 and 28 at the front edges of the dividers, top, bottom and intermediate shelves, provide smooth, rounded surfaces, which eliminate sharp corners and avoid tearing of the clothing, or possible injury to the articles, in depositing them on or removing them from the shelves.

Such rack units have one important use as 90 shelving under ordinary wooden store counters, for carrying reserve stocks of the articles displayed upon the counters. They may be assembled readily in units with the desired length of shelving and the shelving may 95 be adjusted rapidly at levels to suit the requirements of the articles stored in the racks.

It is thought that the invention and many of its attendant advantages will be understood from the foregoing description, and it 100 will be apparent that various changes may be made in the form, construction and arrangement of the parts without departing from the spirit and scope of the invention or sacrificing all of its material advantages, the form 105 hereinbefore described being merely a preferred embodiment thereof. Moreover, it is not indispensable that all features of the invention be used conjointly, as they may be advantageously employed in various sub-combinations and other combinations.

I claim:

1. In a sheet metal shelf or rack construction, the combination with side divider plates having top and bottom front-to-rear extending, inwardly-projecting horizontal flanging, front bulb-fold vertical flanging and rear inwardly-projecting vertical flanging and provided with vertically-superposed horizontal rows of horizontally elongated shelf-supporting louvres projecting upwardly from the inside faces of said divider plates and with a bottom horizontal row of reversely-projecting louvres, of a top, bottom, back and shelving supported by said divider plates, each comprising a plate having projecting side flanging, similarly projecting flanging at one end and bulb-fold flanging at the other end, the top plate and shelving being arranged with the bulb-fold flanging at the front and sup- 120 125 130

and shelving plates being slidably engageable with said louvres, and the back plate being vertically positioned at the rear of the rack with the side flanging thereof engaging the rear vertical flanging of the divider plates, and with its top and bottom flanging engaging the end flanging of the top and bottom plates.

7. In a sheet metal shelf or rack construction, the combination with side divider plates having vertical flanging and provided with shelf-supporting louvres, of a top, bottom, back and shelving supported by said divider plates, each comprising a plate having side and end flanging, the top, bottom, and shelving plates being slidably engageable with said louvres, and the back plate being vertically positioned at the rear of the rack with the side flanging thereof engaging the rear vertical flanging of the divider plates, and with its top and bottom flanging engaging the end flanging of the top and bottom plates.

8. In a sheet metal shelf or rack construction, the combination with flanged divider plates provided with shelf-supporting louvres, of the top, bottom and intermediate rack shelving and the back of the rack, constructed of structurally-uniform plates having side flanging engageable interchangeably with the divider louvres or divider flanging and end flanging engageable mutually with the end flanging of other similar plates.

9. A sheet metal rack construction comprising side plates provided with intermediate shelf-supporting elements, and the top, bottom and intermediate rack shelving and the back of the rack, constructed of structurally-uniform plates the sides of which are engageable interchangeably with the shelf-supporting elements or edges of the side plates and the ends of which are engageable mutually with the ends of other similar plates.

10. A sheet metal rack construction comprising side plates provided with intermediate shelf-supporting elements, and the rack shelving and closure plates made of uniform construction including side and rear edge flanging engageable interchangeably with the shelf-supporting elements or edges of the side or other plates of the rack.

11. A sheet metal shelf rack comprising side plates provided with inwardly extending struck out shelf supporting louvers, a plurality of shelves extending between said spaced uprights and carried in said louvers, said uprights and said shelves having their forward edges provided with a bulb-fold and their sides and rear edges provided with outstanding flanges, the side flanges of the shelf members interlocking with the shelf supporting louvers of the uprights, and a back member for the shelf having outwardly extending flanges formed along its top and side edges,

and a bulb-fold extending along its bottom edge, and the side edges of said back member interfitting within the rear flanged edges of the side members and a top and bottom for the shelf rack comprising shelf members having, respectively, downwardly and upwardly extending lateral flanges along their rear edges, said flanges having detachable interlocking engagement with the rear member.

12. A sheet metal shelf rack comprising side, top, bottom and rear walls comprising substantially rectangular sheet metal members having inwardly extending flanges along each side and one end, the side walls of the shelf rack being provided with a vertical series of shelf supporting louvers, said top and bottom members having their side flanges detachably engaging in the uppermost and lowermost louvers, respectively, of the side members, and said back member fitting within the rear edges of the side wall members.

13. A sheet metal shelf rack comprising side, top, bottom and rear walls comprising substantially rectangular sheet metal members having inwardly extending flanges along each side and one end, the side walls of the shelf rack being provided with a vertical series of shelf supporting louvers, said top and bottom members having their side flanges detachably engaging in the uppermost and lowermost louvers, respectively, of the side members and said back member fitting within the rear edges of the side wall members, the rear-most edge of the top member being interlocked within the inwardly extending flange in the upper edge of the back member.

14. In a sheet metal shelf rack construction, the combination of a pair of spaced apart shelf supporting plates provided with inwardly extending flanges along their upper and lower edges, struck out louvers formed in said shelf supporting plates in spaced relationship from said flanges, a top shelf arranged for interlocking engagement at its opposed edges between the upper flanges of said shelf supporting plates into adjacent struck out louvers thereof.

15. In a sheet metal shelf rack construction, the combination of a pair of spaced apart shelf supporting plates provided with inwardly extending flanges along their upper and lower edges, struck out louvers formed in said shelf supporting plates in spaced relationship from said flanges, a top shelf arranged for interlocking engagement at its opposed edges between the upper flanges of said shelf supporting plates into adjacent struck out louvers thereof, and a bottom shelf arranged for interlocking engagement at its opposed edges between the lower flanges of said shelf supporting plates and the aforesaid struck out louvers thereof.

WALTER N. VANCE.
